US0D1099131S

(12) **United States Design Patent** (10) Patent No.: **US D1,099,131 S**
(45) Date of Patent: ** Oct. 21, 2025

(54) **DISPLAY SCREEN OR PORTION THEREOF WITH GRAPHICAL USER INTERFACE**

(71) Applicant: **Google LLC**, Mountain View, CA (US)

(72) Inventors: **Alexandra Hill Olds**, London (GB);
Yeun Su Shin, San Francisco, CA (US);
Ajinkya Shirish Barve, Sunnyvale, CA (US)

(73) Assignee: **GOOGLE LLC**, Mountain View, CA (US)

(**) Term: **15 Years**

(21) Appl. No.: **29/924,034**

(22) Filed: **Jan. 17, 2024**

(51) LOC (15) Cl. 14-04

(52) U.S. Cl.

USPC **D14/485**

(58) **Field of Classification Search**

USPC D14/489-495, 485-488
CPC H04M 1/724-72484; G06F 3/048-04897

See application file for complete search history.

(57) **CLAIM**

The ornamental design for a display screen or portion thereof with graphical user interface, as shown and described.

DESCRIPTION

The sole FIGURE is a front view of a display screen or portion thereof with graphical user interface, showing the new design.

The dot-dash broken lines in the FIGURE show a display screen or portion thereof and form no part of the claimed design. The evenly spaced broken lines in the FIGURE show portions of the graphical user interface and form no part of the claimed design.

1 Claim, 1 Drawing Sheet
